[57] CLAIM

The ornamental design for a seat, substantially as shown and described.

DESCRIPTION

FIG. 1 is a front perspective view of a seat in the form of an easy chair embodying my design;

FIG. 2 is a side elevational view thereof;

FIG. 3 is a rear elevational view;

FIG. 4 is a top plan view;

FIG. 5 is a side elevational view looking from the opposite side from FIG. 2;

FIG. 6 is a bottom view thereof;

FIG. 7 is a front elevational view of a seat in the form of a love seat embodying my design;

FIG. 8 is a side elevational view of the love seat, the other side elevation having the same appearance;

FIG. 9 is a rear view of the love seat;

FIG. 10 is a top plan view thereof;

FIG. 11 is a bottom view of the love seat;

FIG. 12 is a front elevational view of a seat in the form of a three-seater sofa embodying my design;

FIG. 13 is a rear elevational view of said sofa;

FIG. 14 is a top plan view of the sofa;

FIG. 15 is a bottom view of the sofa; and

FIG. 16 is a side elevational view of the sofa, the other side elevation having the same appearance.
